FILLING MACHINE ADAPTED TO DELIVER
METERED AMOUNTS OF SOLID COMMIN-
NUTED MATERIALS

Charles A. Heisterkamp, Wynnewood, and Morris Dann and John P. Dura, Philadelphia, Pa., assignors, by mesne assignments, to American Home Products Corporation, New York, N. Y., a corporation of Delaware

Application May 3, 1949, Serial No. 91,094

7 Claims. (Cl. 222—1)

1

This invention relates to a filling machine especially adapted to deliver metered amounts of solid comminuted material of high unit value with a minimum of loss and under sterile conditions.

The machine comprises an intermittently moving member containing a metering cavity; in one position of the member a metered charge of the powdered material is introduced into the cavity, and in another position of the member the powdered material is expelled from the cavity, in both cases by the application of differential air pressure. Suction is preferably used for loading the cavity and pressure for discharging it. During the charging of the cavity, the powdered material is retained by suitable screens and we have found it desirable to provide means for cleaning these screens periodically by a scavenging air blast in a direction opposite to the air flow during charging of the cavity. This may conveniently be done when the cavity is in the discharge position.

A source of the powdered material is provided, such as a hopper, suitable located to deliver the material to the cavity in its charging position. Provision is made at the discharge position to deliver the successively metered contents of the cavity, as through a nozzle, into desired receptacles such as vials. The vials may be placed and removed manually, or provision may be made for doing this automatically.

Among the objects of our invention are:

To provide a machine of simple construction capable of metering small amounts of powdered material accurately and without loss; to provide such a machine that may be readily disassembled and assembled; to provide such a machine that may be readily sterilized; and to provide such a machine operable with low maintenance expense.

Other objects and advantages will be apparent from the following description to those skilled in the art.

In the drawings accompanying this specification:

Fig. 1 is a perspective view of our machine showing also associated drive motor, reduction gear and air gages;

Fig. 2 is a side view partially sectioned on the line 2—2 of Fig. 3;

Fig. 3 is a plan view seen from above;

Fig. 4 is an end view, partly in section;

Fig. 5 is an enlarged view of the cavity bar and adjustable cavity; and

Fig. 6 is an enlarged view in section of the wiper ring and associated fittings in opening 66.

2

General construction

Our machine is mounted on a wooden base 1 which supports a steel or cast iron bed plate 2. On the latter is mounted a backbone 3 which in turn supports vacuum valves 4, pressure valves 5, guide 6 and hopper 7.

A reciprocating slide bar 8 is slidably mounted on backbone 3, the right-hand end (viewing Fig. 3) being guided by passing through guide 6. The left-hand end is guided as described below, so that in operation the slide bar has a longitudinal linear reciprocating motion. Projecting from the rear side (upper side, viewing Fig. 3) of the slide bar 8 and rigidly affixed thereto is cam block 9 in the rear face of which is machined a cam groove 10. To the forward (lower, Fig. 3) side of slide bar 8 is affixed valve operating bar 11 by means of gusset plate 12.

On the rear portion of bed plate 2 are mounted two pillow blocks 13 and 14, in which is journaled shaft 15. The axis of this shaft is perpendicular to that of slide bar 8 and in nearly the same plane. A crank arm 16 is fixed on the forward end of the shaft and two pulleys 17 and 18 respectively on the middle portion and rear end of the shaft; pulley 18 is a stepped pulley.

Crank arm 16 bears at its outer end a pin and roller 19, which operatively engage cam slot 10 in cam block 9. Accordingly rotation of shaft 15 causes endwise reciprocation of slide bar 8 and parts of the machine attached thereto. The contour of slot 10 is such that the velocity of slide bar 8 is greatest during the midportions of its strokes and least at the ends.

Shaft 15 may be driven by any conventional means, as by belt 20 connected with stepped pulley 21 of a reduction gear 22 driven by electric motor 23.

Metering slide 24 is rigidly fixed by means of cap screw 25 to the left-hand end of slide bar 8 (viewing Figs. 2 and 3). Slide 24 is formed with a longitudinal rib 26 on its underside having upwardly and inwardly beveled edges 27. Rib 26 is of less width than slide 24, thus providing bottom flange surfaces 28 on which slide 24 may slide. The bottom flange surfaces 28 rest slidably on, and rib 26 slides between, gibs 29 adjustably mounted on backbone 3. These gibs cooperate with guide 6 to ensure longitudinal linear motion of the rigid assembly of slide bar 8 and metering slide 24.

Metering slide

Metering slide 24 is provided with adjustable metering cavity 30 and scavenging port 31.

Metering cavity 30, as shown in Fig. 2, extends completely through metering slide 24, while scavenging port 31 extends only partly through the slide vertically and communicates with the outside through lateral passage 32.

The metering cavity 30 is made adjustable within certain limits by providing it with a movable side wall 33, this movable side wall being the concavely curved end of adjusting slide 34. Longitudinal movement of this slide increases or decreases the volume of cavity 30 as desired. For variations in capacity beyond the range of this adjustment interchangeable metering slides may be provided, having cavities of different sizes.

Adjusting slide 34 is mounted with a close sliding fit in a corresponding slot in the left-hand end (viewing Figs. 2 and 3) of metering slide 24, the slot extending from cavity 30 to the end of the slide. Slide 34 is retained in the slot by means of Woodruff keys 35 sliding in grooves 36 cut longitudinally in the interior walls of the slot. Longitudinal adjustment of adjusting slide 34 in metering slide 24 is effected by means of micrometer screw 37 threaded into plate 38 which bridges the open end of the adjusting slide slot and is screwed fast to the end of metering slide 24 by screws 39. The right-hand end of screw 37 bears against the recessed end of slide 34 at 40, and the left-hand end of screw 37 within its recessed head bears against nut 41 retained on the end of threaded stud 42 by means of screw 43. Stud 42 is threaded into adjusting slide 34 and its positioning in the latter determines backlash in micrometer screw 37. The volume of cavity 30 may be related to calibration indicia 44 on metering slide 24 and adjusting slide 34.

Hopper

Hopper 7 is of generally conical shape but formed with a semi-cylindrical bottom portion 51 in which are mounted agitator paddles 52 on rotatable shaft 53. The latter is journaled in sleeve 54 mounted on the rear of the hopper, and carries at its outboard end pulley 55 which is driven from pulley 17 by belt 56. Hopper 7 is mounted on hopper plate 57 by means of extensions 58 and studs and thumb nuts 59. Hopper 7 is provided with bottom outlet 60 registering with opening 61 in hopper plate 57. The latter is positioned by studs 62 in gibs 29 and maintained at the desired height by spacers 63 through which the studs pass. Wing nuts 64 on the studs hold the hopper plate firmly in place. In addition to opening 61 the hopper plate is also provided with opening 65, spaced from opening 61 approximately the same distance as that separating openings 30 and 31 in metering slide 24.

Wiper rings and connections

When hopper plate 57 is in position, openings 61 and 65 are respectively aligned with openings 66 and 67 provided in the left-hand or hopper end of backbone 3. Since these openings co-operate with the openings in the metering slide 65 during its reciprocations to alternately measure and discharge a desired constant amount of powdered material, provision is made in each case for a yieldable tight sliding fit with the top and bottom surfaces respectively of the metering slide. This arrangement results in reducing to a minimum the contact areas subject to sliding friction. The principle is the same in all cases, namely the use of a wiper ring pressed by an elastic element against the moving surfaces.

In the case of the outlet 60-61 from hopper 7, the opening in hopper plate 57 is recessed around its lower edge to receive and retain wiper ring 68, having an L-shaped section, and live rubber washer 69, which presses ring 68 against the top of slide 24 to form a slidable but powder-tight joint.

The other opening in the hopper plate 57, opening 65, is recessed around its upper edge to receive flange 70 of wiper ring 71. The latter has a bottom portion 72 extending below the hopper plate and an upper portion terminating in a threaded nipple 73. Surrounding ring 71 with a loose fit is union nut 74 which is screwed onto annular fitting 75 fixedly mounted on a plate 57. This annular fitting has an internal diameter slightly larger than that of flange 70 and contains a strong helical compression spring 76 resting on flange 70 and compressed by union nut 74. The effect of this is, of course, to press ring 71 yieldably into contact with the top of slides 24 and 34.

In a similar manner, on the bottom of backbone 3 wiper rings 77 and 78 are retained and biased upwards against the bottom of slides 24 and 34 in openings 66 and 67 respectively by union nuts 79 and 80, annular fittings 81 and 82, and helical compression springs 83 and 84 bearing on ring flanges 85 and 86.

Wiper rings 77 and 78 differ from each other and from ring 71. Ring 77 is internally threaded at its lower end and has a narrow internal flange 87 at its upper end. Against the latter is pressed a fine-meshed stainless steel screen 88 and below the screen a felt filter 89, both retained by plug 90 screwed into the internal thread of wiper ring 77. The upper end of plug 90 is perforated with a number of small drilled holes 91 and the remainder is drilled out to a large axial bore which is internally threaded to receive externally and internally threaded pipe adapter 92. Wiper ring 78 has an elongated outlet nozzle 92' adapted to enter the neck of a vial or other container into which the metered powdered material is destined to be delivered. Union nut 80 also differs from union nuts 74 and 79 in being more widely spaced from the associated wiper ring, in being provided with a soft rubber covering 93 against which vial tops may be pressed during filling, and in having a side outlet nipple 94 adapted to be connected with a rubber tube 95 leading to a dust receiver (not shown) or to hopper 7. A spiral cone of light spring wire 96 or other coarse screen may advantageously be placed loosely in outlet nozzle 92' to break up lumps of powdered material passing through the nozzle.

Air system

Air flow in our machine is controlled by vacuum valve 4 and pressure valve 5. These are of identical construction but mounted on backbone 3 in mirror-image relation to each other. Construction will be described with reference to vacuum valve 4, corresponding parts of pressure valve 5 being indicated in the drawings by the same index numbers primed. Each valve is duplex, controlling two air circuits simultaneously. The valve block consists of a cover 101 and a body 102. Cover and body are each provided with a pair of registering ports 103, 104 and 105, 106 tapped for pipe connections. A pair of slots 107 and 108 parallel to each other and to slide bar 8 is machined in the body 102, receiving with a close sliding fit valve slides 109 and 110. Each slide is provided with a stop 111 and

112 at one end and an upstanding flange 113 and 114 at the other. The flanges are drilled and tapped to receive adjustable tappet screws 115 and 116 carrying lock nuts 117 and 118. Compression springs 119 and 120 bearing on the valve covers and slide flanges and surrounding the tappet screws bias the valve slides in the direction of the flanged ends. Each slide is provided with a port 121 and 122. The ports are so located that, when the slides are in biased position, the ports are out of registry with cover and body ports but, when the slides are moved longitudinally against the compression springs, slide ports 121 and 122 come into registry with cover and body ports and clear passages through the valve are provided. This is shown in valve 5, Fig. 3. Since valve operating bar 11 reciprocates with constant amplitude, the travel of the valve slides may be regulated by adjusting the tappet screws 115, 116, 115' and 116'; a valve may even be put out of action altogether by turning the tappet screw home, as is shown in Fig. 3 for slide 109 and tappet screw 115.

Air pressure and vacuum for our machine may be obtained from any suitable source and may advantageously be supplied respectively through a pressure service line and reducing valve 123 associated with a pressure gage 124 and a vacuum service line associated with a vacuum gage 125, though these form no part of our invention.

Suction is applied from the vacuum service line through pipe 126 connecting with port 106 on top of valve 4 (the rear half of valve 4 is not used in the embodiment described herein). A suction pipe 127 connects bottom port 106 of valve 4 with a T 128, the branch of which is screwed into bottom port 106' of valve 5. To the third connection of T 128 is connected one end of rubber tube 129, the other end of the tube being connected to adapter 92 by nipple 130 as shown in Fig. 2. This end of tube 129 is shown disconnected in Fig. 1.

Air pressure is supplied by the service line through pipe 131, T 132 and branch pipes 133 and 134 respectively to top port 104' of the front half and bottom port 105' of the rear half of valve 5. Upper port 103' of valve 5 is connected by rubber tube 135 with wiper ring 73 by means of suitable fittings.

Lubrication

In addition to conventional oil holes for the rotating shafts, grease cups are provided as at 136, 137 and 138 for lubricating the slide bar guide 6, cam groove 10 and metering slide gibs 29.

Operation

With hopper 7 charged with the powdered material to be metered and with shaft 15 being operated by motor 23 and reduction gear 22 through the pulleys and belts shown, the operation cycle is as follows.

The powdered material in hopper 7 is continuously agitated and thus maintained in a fluent condition by paddles 52 on shaft 53 driven at slow speed by pulley 55 connected by belt 56 with pulley 17 on shaft 15.

Rotation of crank arm 16 on shaft 15 causes reciprocation of slide bar 8 and metering slide 24 through the action of crank pin and roller 19 on cam groove 10 in cam block 9 carried by slide bar 8. Assuming the slide assembly 8-24 in its extreme left-hand position as shown in Fig. 2, it will be moved to the right until metering cavity 33 is under outlet openings 60 and 61 in hopper 7 and hopper plate 57. Simultaneously valve oper-

ating bar 11 will have moved to the right, releasing pressure on springs 119 and 120, thus permitting both parts of valve 5 to close, and by pressure on tappet screw 116 will have compressed spring 120 and opened valve 4 by moving valve slide 110 until port 122 registers with ports 104 and 106. The opening of this valve will cause a suction wave to travel from hopper 7 through openings 60 and 61, metering cavity 30, screen 10 and felt 88 and 89, perforated plug 90, tube 129 and pipes 127 and 126 and associated fittings, thereby drawing a charge of powdered material into metering cavity 30, where it is momentarily maintained by screen 88 and felt 89.

Continued rotation of shaft 15 will move the slide assembly 24-8 to its extreme left-hand position where metering cavity 30 is in registry with openings 65 and 67. As the metering cavity 30 slides past wiper rings 68 and 77 a precisely determined charge of powdered material will be cut off and isolated in it. Simultaneously with the movement of the slide assembly, movement of valve operating bar 11 will close valve 4 by releasing pressure on spring 120, thus cutting off suction, and at the end of its stroke will open both halves of valve 5 by the action of valve operating bar 11 on tappet screws 115 and 116, moving slides 109 and 110' against the pressure of springs 119' and 120', bringing slide ports 121' and 122' into registry with valve ports 103', 105' and 104', 106' respectively.

This action has a double effect: (1) Scavenging of the filter and screen; (2) expulsion of the metered charge of powdered material from the machine, e. g. into a vial.

The scavenging results from the admission of a pressure wave from the compressed air service line through pipe 131, T 132, pipe 133, downward through ports 104', 122' and 106' of valve 40 5, through tube 129, opening 66, perforated plug 90, felt 89 and screen 88. The effect of this scavenging pressure wave is to blow residual powdered material and any loose felt fibers or other traces of detritus from the surface of the felt-screen filter assembly, to loosen the felt fibers and clear the interstices; thus preventing the filter from becoming clogged and impervious to air; and to expel the loosened material from the machine through port 31 and passage 32, thus presenting a clean pervious filter surface to each charge. This is particularly desirable in metering pharmaceutical materials such as penicillin. The expelled material may be collected in a suitable receiver and reworked for recovery of the powdered product.

Expulsion of the metered charge results from passage of a pressure wave from the compressed air service line through pipe 131, T 132, pipe 134, upwards through ports 105', 121' and 103' of valve 5, through tube 135 and opening 65. This pressure wave expels the metered charge from metering cavity 30, downwards through opening 67, wire helix 96 and nozzle 92' into a container such as a vial which has been placed, either manually or mechanically, under the nozzle; the mouth of the container is advantageously held in contact with rubber coating 93 during this operation. Any air-suspended dust that may result is blown out through nipple 94. This may be collected separately in any desired form of collector or, since it is uncontaminated, may be returned directly to hopper 7, depending on its character.

Continuing revolution of shaft 15 repeats the cycle.

Example

In filling vials with crystalline penicillin powder and with manual positioning and removal of vials, satisfactory operation is obtained at a rate of 28 cycles per minute, the nominal charge being 1.95 g. per vial and the maximum variation in charge being a little over $\pm 2\%$, or a little over +40 mg. A vacuum of 20-25 inches of mercury may be used for filling the metering cavity and an air pressure of 2 lb. per sq. in. for scavenging and discharging the metered penicillin. 98 percent or more of the material in hopper 7 is metered into the vials.

All parts of the machine coming in contact with the penicillin are of stainless steel, and these parts are sterilized before the run by washing with alcohol and drying in a current of sterile air. Disassembly of the hopper, slide and rubber air hoses, cleaning, sterilization, drying and re-assembly require about $\frac{1}{2}$ hour; no special tools are needed.

Modifications

The main features of the machine described above are considered essential or highly advantageous for metering many materials, but, as will be apparent to those skilled in the art, modifications may be made without departing from our invention where the character of the metered material permits. For example, with some free-flowing materials the air-pressure differential at the discharge nozzle may be produced by suction instead of pressure, and when extreme purity of product is not essential and a non-clogging material is being handled, the scavenging step and means for effecting it may be omitted. The detailed disclosure of an embodiment of our invention set forth above is thus intended to be exemplary only and not to limit the invention, the scope of which is defined in the appended claims.

From this disclosure it will be seen that we have devised a simple, effective and efficient machine for successively metering and delivering precisely measured amounts of comminuted material, that the machine is readily disassembled for cleaning and sterilization and readily reassembled without the use of special tools, that surfaces subject to sliding friction are reduced to a minimum by the use of wiper rings, that the provision of an adjustable metering cavity and readily interchangeable metering slides gives the machine great flexibility and that all parts are easily accessible for maintenance or replacement when worn.

We claim:

1. A machine adapted to meter successive amounts of solid comminuted material comprising: (1) a bulk container for said material, (2) a metering slide, (3) a discharge port, (4) means for providing differential air pressure, (5) power means to move the metering slide, and (6) valve means controlling the differential air pressure; the bulk container having a material outlet in sliding contact with the metering slide; the metering slide having a metering cavity and being movable in its own plane by said power means to bring the metering cavity successively into registry with the material outlet of the bulk container and the discharge port; the said valve means being structurally independent of said metering slide and being operated synchronously therewith by said power means to effect charging of said cavity when in registry with the material outlet of the bulk container and discharge of the contents of said cavity when in registry with the

discharge port by application of short regulated pulses of differential air pressure to said comminuted material; said discharge port comprising a nozzle in sliding contact with said metering slide; and the sliding contact between the metering slide and the material outlet of the bulk container and between the metering slide and the discharge port being provided by means of rigid spring-loaded rings resiliently bearing on the metering slide.

2. A machine as defined in claim 1 in which the metering cavity passes with a substantially uniform bore completely through the metering slide and which comprises means for charging the cavity when in registry with the material outlet of the bulk container by the application of regulated pulses of suction, a screen to retain the charge in the cavity during the application of suction, and means for discharging the contents of the cavity when in registry with the discharge port by the application of regulated pulses of air pressure.

3. A machine as defined in claim 2 which also includes means for scavenging the screen by the reverse application of a pulse of air pressure while the contents of the metering cavity is being discharged and means for discharging the scavenged material separately from the metered material.

4. A machine as defined in claim 1 in which one wall of the metering cavity is movable in the plane of the metering slide to desired different positions by means of a micrometer screw, whereby the machine is adapted to meter desired different amounts of comminuted material.

5. A machine adapted to meter successive amounts of solid comminuted material comprising: a bulk container for the comminuted material having a bottom outlet, a metering slide mounted for linear reciprocating movement under the bulk container, an air port containing an air-pervious screen mounted under the metering slide and in registry with the bottom outlet of the bulk container, a discharge port mounted under the metering slide in its line of travel at a distance from said air port, a second air port mounted above said metering slide and in registry with the discharge port, wiper rings associated with said bottom outlet, said discharge port and said air ports resiliently biased into sliding contact with the metering slide, a metering cavity in the metering slide passing with substantially constant bore completely therethrough, the metering cavity having a side wall movable in the plane of the metering slide

55 by means of a micrometer screw to effect desired variations in the volume of the metering cavity, a scavenging port in the metering slide spaced lengthwise from the metering cavity a distance approximately equal to the distance of said second air port from the bottom outlet of the bulk container, the scavenging port having an opening through the bottom and an opening through an edge of the metering slide, power means to reciprocate the metering slide with a stroke of such length that in one position the metering cavity is in registry with the bottom outlet of the bulk container and in another position with the discharge port, a source of air suction connected with said first air port, a source of air pressure connected with said first and second air ports, and valves in the air connections operated in synchronism with the reciprocations of the metering slide to apply suction to said first air port when the metering cavity is in registry

with the bottom outlet of the bulk container, thereby charging the cavity with comminuted material, and to apply pressure to said first and second air ports when the scavenging port and metering cavity are respectively in registry therewith, thereby scavenging the screen and discharging the contents of the cavity through the discharge port.

6. A process for metering successive small amounts of solid comminuted material which comprises the following steps: providing a bulk supply of solid comminuted material, transferring a portion of the material at a loading station to a partially enclosed three-dimensional metering cavity by the application of a regulated pulse of differential air pressure of short duration to said material while supporting said material in said metering cavity on an element pervious to air but impervious to said material and exterior to said metering cavity, moving said metering cavity from the loading station to a discharge station and at the same time removing excess material from said metering cavity by moving an unenclosed side thereof past a wiper element towards the discharge station, discharging the contents of said metering cavity at the discharging station by a second applica-

tion of a regulated pulse of differential air pressure of short duration to the comminuted material contained in it, and reversing the travel of said metering cavity at the loading station and discharge station respectively immediately before and immediately after the application of said pulses of differential air pressure.

7. In combination with the process defined in claim 6, the further step of scavenging the air-pervious supporting element with a reverse application of a pulse of differential air pressure simultaneously with the discharge of the metering cavity, and discharging the purged material separately from the metered material.
